ENGINE PRIMER

Arthur L. Parker and Joseph F. Melichar, Cleveland, Ohio, assignors to The Parker Appliance Company, Cleveland, Ohio, a corporation of Ohio

Application November 27, 1944, Serial No. 565,240

7 Claims. (Cl. 103—2)

1

The present invention relates generally to primers for internal combustion engines or the like, arranged to feed a priming charge to one or more of a series of such engines through a selector valve for opening and closing a plurality of outlets.

An object of the invention is to provide in an engine primer of the type above referred to, a novel selector valve indexing and locking means, in combination with a novel indicating means for each position of the selector valve with respect to any one of a plurality of outlet ports.

A further object is to provide in an engine primer including a selector valve arranged with a plurality of outlets and a piston adapted to detachably connect therewith, novel valve indexing means and locking means whereby the primer piston is locked against reciprocating movement when the selector valve is "off" or being turned from one outlet to another, and whereby the piston is detachable therefrom for reciprocation independently of the valve when the selector valve is "on".

Still a further object is to provide in an engine primer, a novel means, whereby each respective position of a selector valve is positively indicated to the operator.

These and other objects I attain by the construction in the accompanying drawing, wherein one embodiment of the invention is shown for the purpose of illustration, and wherein:

Figure 1 is a longitudinal cross section view of a primer embodying the invention;

Figure 2 is a top plan view in elevation of the assembled novel indexing, locking and indicating means of the primer;

Figure 3 is a transverse cross section view taken on the line 3—3 of Figure 1;

Figure 4 is a transverse cross section view taken along the line 4—4 of Figure 1, showing the detachable connection between the selector valve and the primer piston;

Figure 5 is a transverse cross section view taken along the line 5—5 of Figure 1;

Figure 6 is a top plan view of a novel valve abutment plate, such as may be used with our device;

Figure 7 is a plan view of the inner side of the novel index plate adapted to receive the valve position indicator ring;

Figure 8 is a cross section view taken along the line 8—8 of Figure 7;

Figure 9 is a cross section view showing the piston disconnected from the selector valve.

Referring to the drawing and first with par-

2

ticular reference to Figure 1, the primer broadly includes a pump cylinder 10, a piston 11 with an enlarged head portion 12 mounted therein for rotation and/or reciprocation by means of an operating handle 13 secured to an end of the piston opposite the enlarged head portion 12, an inlet check valve 14, a selector valve 15 detachably connected to the piston head 12, and novel means for indexing, locking and indicating each respective position of the selector valve 15 adjacent to the operating handle 13 and cooperating therewith.

The pump cylinder 10 is flared outwardly at its lower end to provide an enlarged chamber 16. The chamber 16 contains a threaded aperture in the side wall for receiving the inlet check valve 14, which may be a self-contained nipple in which is mounted a ball 17 and a spring 18. Thus the primer can readily be mounted on an instrument panel 19 having a hole of a diameter but slightly larger than the enlarged chamber 16, when the nipple is temporarily removed.

Within the enlarged chamber 16 is the selector valve 15, a spring 20, a spring abutment plate 27 and an outlet spring ball check valve 22. Valve 15 has a seating end 24 preferably of graphitic material bonded thereto. The valve 15 and end 24 are provided with a central passage 25 therethrough, and a radially extending passage 26 adjacent the seating surface of the valve end 24. The passage 26 is adapted to be brought into or out of alignment with any one of a plurality of outlet ports 23 in a head 30 secured as by bolts 31 in the rim of cylinder 10 by selectively rotating the valve unit 15. The coupling between the end of the cylinder 10 and head 30 may be made fluid-tight by any suitable device, such as gasket 32.

Rotation of the valve unit 15, which may be any suitable type of rotary valve is accomplished by rotation of the handle 13 secured to the piston 11 opposite to the enlarged piston head 12, which detachably connects with the other end 33 of the valve 15. This end 33 of the selector valve 15 is non-circular in cross-section; and is engageable in a transverse groove of similar cross-section in piston head 12. The spring abutment plate 27 is adapted to engage with an annular shoulder 34 at the upper end of the chamber 16, and is apertured so as to fit over the non-circular end 33 of the selector valve 15, and to provide for passage of fluid into the cylinder 10, as shown in Figure 6. Thus, when the piston is pulled upward, as shown in Figure 9, the spring 20 expands and causes the abutment plate 27 to engage with the shoulder 34, whereby the expanding action

of the spring 20 likewise moves the valve 15 and presses the seat 24 against a flat seating surface on the cap or head 30. Obviously, the spring 20 should have greater tension than the opposing suction forces created in the cylinder during outward movement of the piston 11, so that the selector valve unit 15 will remain seated on the seating surface of head 30. The piston head 12 has an annular groove in which is mounted a sealing ring 35, and also has on its upper face a cushioning means, such as a rubber ring 36, see Figure 9.

The piston 11 opposite to its enlarged head portion 12 is guided and operated by means mounted on the upper extremity of the cylinder 10, which cylinder is provided with a mounting flange 38. The flange 38, as shown in Figure 1, is adapted to be secured to the instrument panel 19, and to support and mount an indexing ring 39 adapted to cooperate with a radial lug 40 carried by a skirt portion 41 on handle 13, as hereinafter to be described.

Extending from the flange 38 is a nipple 42 counterbored, for example to define a shoulder 43 against which seats the end face of a piston 25 guide sleeve 44, and which is engageable with the cushion ring 36 on the enlarged head of the piston 11, to thereby limit the outward movement thereof.

Concentrically positioned around the sleeve 44 on the mounting flange 38 is mounted the novel selector valve indexing ring 39, the lower locking skirt portion 41 of the handle 13 with the radial locking lug 40 adapted to cooperate with the indexing ring for locking the piston 11, and the novel indicating ring 50, each as best shown in Figures 2, 3, 7 and 8. The indexing member comprises the plate 39 centrally formed as by counter boring or the like to provide a flange. The continuity of this flange is interrupted by 40 equal spaces 46, so as to define segments 47, see Figure 7, which segments on the inner side adjacent the mounting flange are pressed in or partially cut out to provide recesses 48 for cooperation with the lug 40 carried by the skirt 41 of handle 13 and thus yieldably retain the handle in an off position, whereby no fluid can be passed from the inlet valve 14 to any of the outlet ports 28 regardless of the pressure at the inlet, and whereby the piston 11 is locked against reciprocation. The side walls 49 of the recesses 48, as shown in Figure 8, are preferably inclined or rounded, so that the handle 13 need only to be rotated to disengage the lug 40 therefrom. Otherwise if the side walls were square and sharp it would be necessary to depress the handle 13 before turning it.

The mounting flange 38 and the flanged segments 47 of the indexing plate 39 define between them an annular countersunk bore 45, see Figure 60 8, in which is disposed a novel indicator means, such as a split ring 50, preferably made of colored plastic, painted metallic material or the like. The outer diameter of the indicator ring 50 is normally larger than the inner bore 45 of the indexing ring or plate 39. Thus, when the split ring 50 is placed within the indexing ring 39, it must be contracted, and therefore it yieldably engages with the inner walls of the index ring 39. Also, when the indicator ring 50 is thus confined within the bore 45 of the index ring 39, there remains a gap 51 therein, see Figures 2 and 3, which is equal to the spaces between each of the index rings flanged segments 47. Accordingly, the indicator ring 50 has one portion 70 75

adapted to register with any one of the spaces 46 between one of the flanged segments 47, whereby no portion of the indicator ring 50 is visible, while at the other spaces 46 portions of the indicator ring 50 are clearly visible. Thus, assuming that a red plastic index ring 50 is being used, and the operator sees the red plastic material at all the spaces 46, he knows that the corresponding outlet ports 28 are off, and likewise whenever he sees no red plastic material at one of the spaces 46 he knows that the corresponding outlet port is open, and fluid is passing to that particular engine when the piston 11 is reciprocated.

Thus, for example, when the handle 13 is in a 45° position with its lug 40 engaged in one of the recesses 48 on the inner side of one of the segments 47, the ports 28 are all closed. In this position the flanged segments 47 prevent reciprocation of the piston 11, and the selector valve unit 15 is held in off position wherein the radial passage 26 is out of communication with any of the outlet ports 28. The spring 20 holds the selector valve unit 15 seated on the flat inner seat surface of the cap or head 30, and also transmits pressure through the piston 11 to handle 13, whereby the lug 40 is yieldably forced and held in engagement with the bottom wall of the recess 48, with which it is aligned. As the gap 51 of the red plastic indicator ring 50 turns with the lug 40, the ring gap 51 will be disposed in a 45° position under one of the flanged segments 47 and the solid portions of the red plastic indicator ring are visible at all four spaces 46. This indicates that all of the outlet ports are closed.

Operation

In order to operate the primer to pump fuel from the selected upper outlet port 28, as shown in Figure 1, the handle 13 is turned until the arrow 55 marked thereon is vertical and the lug 40 brought into alignment with the selected space 46 corresponding to the upper outlet 28. As the handle 13 is thus turned lug 40 disengages from the recess 48 and causes the piston 11 to slightly compress the spring 20, so that as soon as the lug 40 comes into alignment with the space 46 corresponding to the selected upper outlet 28, the handle 13 may be released and the spring 20 will force the piston 11 and handle 13 outward, thereby disengaging the lug 40 from a flanged segment 47 through the space 46.

Because of the detachable tongue and groove connection between the piston head 12 and the end 33 of the selector valve 15 rotation of the handle 13 to the aforesaid free position likewise rotates the valve, to thereby bring the radial passage 26 into alignment with the selected upper outlet port 28. When the handle 13 reaches its point of outward movement, as above described, the tongue and groove connection between the piston head 12 and the valve end 33 completely releases, slightly before the lug 40 rises completely out of the confines of space 46 between two of the flange segments 47.

Now, as the lug 40 is completely released from the flanged segments 47, the handle 13 may be pulled outward and reciprocated, if desired, to draw fuel into the cylinder 10. During this outward stroke of the piston 11, the spring 20 yieldably holds the valve in any predetermined set position, such as above described, and also the red indicator ring 50 will remain in any such predetermined set position because of its frictional engagement with the index plate 39. Therefore

after the lug 40 has been raised from the confines of any selected space 46, it is immaterial whether the handle 13 and piston 11 are rotated or not. Following this operation and positioning of the handle, the gap 51 in the indicator ring 50 will be opposite the selected upper space 46, as shown in Figure 2, and the remainder of the red indicator ring 50 can be seen in all of the spaces 46 except the selected one, where the gap 51 in the ring 50 exists. Thus, this indicates that a port 28 corresponding to the selected space 46 is open.

Obviously, when the piston 11 is pulled outwardly the suction unseats the inlet check valve 14 and the cylinder 10 fills up with fluid; and when the piston is pushed inwardly the outlet check valve 22 opens, and the fluid in the cylinder 10 is forced out through the selected upper port 28.

When it is desired to turn the primer off, the handle 13 is turned so that lug 40 aligns with space 46 and the gap 51 in the indicator ring 50. With the lug 40 in this position, the handle 13 is then forced inwardly, and the groove in piston head 12 engages with the non-circular end 33 of selector valve 15. Rotation, if now imparted to the handle 13, approximately 45° in either direction, will turn the selector valve 15 to an off position, while correspondingly rotating the indicator ring 50 and the lug 40 again becomes engaged in one of the recesses 48 behind one of the segments of the flange 45, to thereby yieldably hold the valve unit 15 in an off position and lock the piston 11 against reciprocation.

While the present invention has been described in connection with only one form of device, such as the engine primer illustrated in the accompanying drawing, it is to be understood that it may also have utility for use with other devices for dispensing fluid or the like. Accordingly, it is to be understood that as various other modifications and uses for our invention may suggest themselves, we do not wish to be limited to the specific apparatus disclosed, but desire the appended claims to be construed as broadly as permissible in view of the prior art.

We claim:

1. In a liquid dispensing device comprising a pump having a reciprocating piston, a valve associated with said pump for controlling the discharge of fluid from the pump through a plurality of outlets, means whereby said valve and said piston may be coupled together when said piston is at the end of its compression stroke, so that rotation of the piston will shift said valve to different positions with respect to said outlets; the combination of a handle adapted to rotate said piston, a lug on said handle, and an index member adjacent said handle having a plurality of openings therein corresponding to each of said outlets, said lug being adapted to be aligned with one of said openings in the index member when the handle is rotated, to thereby correspondingly shift said valve into alignment with one of said outlets known to correspond with the selected opening in said index member.

2. In a liquid dispensing device comprising a pump having a reciprocating piston, a valve associated with said pump for controlling the discharge of fluid from the pump through a plurality of outlets, means whereby said valve and said piston may be coupled together when said piston is at the end of its compression stroke, so that rotation of the piston will shift said valve to different positions with respect to said outlets; the combination of a handle adapted to rotate said

10 piston, a lug on said handle, an index member adjacent said handle having a plurality of openings therein corresponding to each of said outlets, said lug being adapted to be aligned with one of said openings in the index member when the handle is rotated, to thereby correspondingly shift said valve into alignment with one of said outlets known to correspond with the selected opening in said index member, and yieldable means mounted around said valve adapted to thrust said lug upward from said index member, while holding said valve fixed in its selected position to provide for the pumping operation of said piston independently of the said valve.

3. In an engine primer including a pump with a piston and a selector valve adapted to control a plurality of outlets, means for operating said piston detachably connectable to said valve so as to selectively shift said valve during one position of the piston to align with one or none of said outlets upon rotation of said means, and means associated with said first-named means adapted to provide for a predetermined rotation of said valve for the selection of a desired outlet during operation of the piston or adapted to lock said piston against operation upon a predetermined rotation of said valve out of alignment with any of said outlets.

4. In an engine primer including a pump with a piston and a selector valve adapted to control a plurality of outlets, means for operating said piston detachably connectable to said valve so as to selectively shift said valve during one position of the piston to align with one or none of said outlets upon rotation of said means, means associated with said first-named means adapted to provide for a predetermined rotation of said valve for the selection of a desired outlet during operation of the piston or adapted to lock said piston against operation upon a predetermined rotation of said valve out of alignment with any of said outlets, and means mounted between said first named means, and said second named means adapted to provide visible indications representative of the on and off positions of said selector valve with respect to said outlets.

5. In an engine primer including a cylinder having a reciprocating piston therein capable of free rotation and a selector valve adapted to open and close a plurality of outlets, a handle for operating said piston within said cylinder, said handle having a skirt portion with a lug thereon, said piston having an enlarged head detachably connectable with said valve so as to provide for rotation thereof to selected position with respect to said outlets upon rotation of said piston, an annulus of larger internal diameter than the exterior of said skirt portion having an inwardly projecting flange mounted on the upper end of said cylinder, said flange being divided into a plurality of spaced segments to thereby define spaces therebetween corresponding in number and position to said valve controlled outlets, and a plurality of depressions centrally disposed on the inner side of each of said segments adapted to be engaged by the lug on said skirt portion of the handle when the outlets are closed by said valve to thereby lock said piston against reciprocation in said cylinder.

6. In an engine primer including a cylinder having a reciprocating piston therein capable of free rotation and a selector valve adapted to open and close a plurality of outlets, a handle for operating said piston within said cylinder, said handle having a skirt portion with a lug thereon,

said piston having an enlarged head detachably connectable with said valve so as to provide for rotation thereof to selected positions with respect to said outlets upon rotation of said piston, an annulus of larger internal diameter than the exterior of said skirt portion having an inwardly projecting flange mounted on the upper end of said cylinder, said flange being divided into a plurality of spaced segments to thereby define spaces therebetween corresponding in number and position to said valve controlled outlets, a plurality of depressions centrally disposed on the inner side of each of said segments adapted to be engaged by the lug on said skirt portion of the handle when the outlets are closed by said valve to thereby lock said piston against reciprocation in said cylinder, and a split ring of yieldable material and contrasting color with respect to said annulus in frictional engagement within the bore of said annulus and concentrically positioned around said skirt portion of said handle, said ring

when so mounted having a gap at its split portion adapted to conform to the width of the spaces between each of said segments, and said lug on said skirt portion of the handle, whereby upon rotation of said handle and said piston to shift said valve the lug likewise rotates said ring to indicate the open or closed condition of the said valve controlled outlets.

7. In an engine primer of the class described having a cylinder, a reciprocating piston therein, a piston locking means carried by the piston, a selector valve adapted to control the discharge of fluid from the cylinder, a fixed indexing member for said valve, locking means associated with said indexing member for engagement with the locking means carried by said primer piston, and means mounted in said indexing member adapted to indicate the on and off positions of said valve.

ARTHUR L. PARKER,
JOSEPH F. MELICHAR.
